UNITED STATES PATENT OFFICE.

NORBERT M. LA PORTE, OF BALTIMORE, MARYLAND.

EXHAUST-REGULATOR.

Specification of Letters Patent. Patented July 4, 1916.

1,189,704.

Application filed October 4, 1915. Serial No. 54,034.

To all whom it may concern:

Be it known that I, NORBERT M. LA PORTE, a citizen of the United States of America, residing in the city of Baltimore, State of Maryland, have invented certain new and useful Improvements in Exhaust-Regulators, of which the following is a specification.

With the exhaust operated cooling device described in my Patent No. 1,138,962, a slight difficulty may in some instances be encountered owing to lack of pressure and velocity in the exhaust gases under low throttle conditions, as when the engine is idling. This would manifest itself by evidence of insufficient cooling when the engine is idling, and would be most apparent with motors having a comparatively low proportion of radiator surface to piston displacement, for the heat generated under such circumstances, though sufficient to cause boiling if not properly dissipated, is slight compared to that generated under heavy loads and full throttle conditions. In order to overcome this difficulty due to lack of pressure in the exhaust at low throttle which may cause a disproportionate decrease in the motive power derived from the exhaust and utilized in cooling, I provide means which operates automatically to prevent decrease of exhaust pressure below a certain point. However, as an increase of the exhaust pressure at full throttle or under ordinary running conditions is objectionable, this device is so arranged that it has no effect when the throttle is open and the car is running free or the engine is pulling hard, as on an up-grade or in heavy going.

In the form of the invention illustrated, the device consists of a valve in the exhaust pipe, mounted on an eccentric pivot and weighted or otherwise controlled so that it tends to close or diminish the opening at low pressures or low throttle, but swings freely open so that its effect is negligible at increased pressures and velocities as when the throttle is open to the full or at medium throttle opening as when the car is running free.

In the accompanying drawings I have illustrated so much of an automobile engine provided with an exhaust operated cooling system in connection with my exhaust check, as is necessary to a full understanding of my invention.

Figure 1 is an elevation illustrating the entire cooling system, exhaust manifold and outlet; Fig. 2 is a detail view of the muffler and exhaust pipe beyond the muffler; Fig. 3 is an illustration of an exhaust check valve of one type; Fig. 4 is a similar illustration of another valve slightly different as to its details; Fig. 5 shows another form of exhaust pressure regulating valve; and Fig. 6 is a detail view showing a portion of the gas tube and non-return check valve.

Referring to the drawing by numerals; I have shown in Fig. 1 an engine casting 1, radiator 2, top and bottom connections 3 and 4 from the water jacket to the radiator, an exhaust circulator 5 of the type described in my Patent No. 1,138,962, consisting of a nozzle 6 in the bottom radiator connection and a pipe 7 leading from the exhaust manifold 8 to the nozzle 6. Preferably, there is a non-return check valve 9 in the pipe 7.

The circulator as shown is operative under all conditions, but at very low throttle the circulating effect is less than is found necessary in some installations, and to overcome this difficulty, an exhaust regulating or check valve 10 has been provided in the exhaust pipe 11.

In the form of the invention shown in Figs. 1 to 3, the exhaust regulating valve 10 of the butterfly type, is mounted on an eccentric transverse pivot 12 so that when the pressure and velocity of the exhaust are sufficient, the valve is thrown wide open and held in that position so that it has practically no effect on the exhaust pressure, but when the throttle is closed and the volume of the exhaust gases is so decreased that the pressure and velocity are reduced, the effect of the regulating valve becomes noticeable as it tends to close and imposes on the exhaust a pressure corresponding to this tendency.

In Fig. 3 I have shown a weight 13 affixed to the valve on the lower side which comprises the greater portion of the valve area. The effect of gravity is thus increased and the valve thus adds several ounces to the minimum exhaust pressure, but the weight is so small that it does not impart sufficient closing tendency to the valve to have any effect on the exhaust pressure when the throttle is at an intermediate or full open position.

In Fig. 4 I have shown a lever arm 14 con-

nected to the pivot 15 of the valve and a weight 16 on the lever. While the effect of the weight is slightly increased, the operation is substantially the same as is that of the valve 5 shown in Fig. 3.

In Fig. 5, I have shown still another form having an arm 17 on the valve pivot and a spring 18 connected to the end of the arm and tending to close the valve.

- 10 The operation is believed to be apparent from the description taken in connection with the preamble and the drawings. The object of the device is to regulate the exhaust pressure when the throttle is practically closed and the engine is idling or the car is running down-hill. Under these circumstances, the tendency of the valve to close imparts a corresponding pressure to the exhaust but the valve is so mounted that 15 it is held wide open by the velocity of the exhaust under conditions of normal or full and intermediate throttle and has no appreciable effect on the exhaust or back pressure, for it will of course be apparent that 20 while an increase of back pressure may be important at full or intermediate throttle positions, the increase of back pressure at low throttle is so slight as to have no harmful effect on the operation of the engine. 25
- 25 I have thus described various embodiments of my invention specifically and in detail in order that its nature and operation may be fully understood; however the specific terms herein are used in their descriptive rather than in their limiting sense and the scope of the invention is defined in the 30 claims.

I claim—

1. In an internal combustion engine, a 40 cooling system including a radiator, a water jacket and suitable connections, a circulating device operated by the exhaust having a tube leading a portion of the exhaust gases from the exhaust pipe or manifold to supply the circulator, and means for regulating the exhaust pressure consisting of a valve in the exhaust pipe beyond the tube, the valve being mounted to open freely in response to 45 exhaust pressure.
2. In an internal combustion engine, a cooling system including a water jacket, a radiator and a circulating device operated by the exhaust, means for regulating the exhaust pressure at low throttle positions in the form of a valve in the exhaust pipe opening in the direction of and in response to the exhaust pressure, and means tending to close the valve against slight pressures. 55
3. In a cooling system for internal com-

bustion engines consisting of a water jacket, a radiator and a circulating device operated by the exhaust, means for regulating the exhaust at low throttle positions in the form of a valve in the exhaust pipe, and an eccentrically placed pivot on which the valve 60 is mounted to swing open in the direction of the exhaust current, the valve having a slight tendency to rotate about its pivot to closed position.

4. An internal combustion engine having 70 a cooling system consisting of a water jacket, a radiator, a circulating device in the form of a nozzle in the circulating system, means connecting the nozzle to the exhaust pipe, means for regulating the exhaust pressure 75 consisting of a valve in the exhaust pipe beyond the pipe leading to the nozzle, and means giving the said valve a slight tendency to close so that it resists and thus increases the slight exhaust pressures but 80 opens freely in response to increased exhaust pressures.

5. An internal combustion engine having a cooling system consisting of a water jacket, a radiator, a circulating device in the form 85 of a nozzle in the circulating system, means connecting the nozzle to the exhaust pipe, means for regulating the exhaust pressure consisting of a valve in the exhaust pipe beyond the pipe leading to the nozzle, the 90 valve being pivotally mounted so that in open position the passage is substantially unobstructed, and means giving the said valve a slight tendency to close so that it resists and thus increases slight exhaust pressures but 95 opens freely in response to increased exhaust pressures.

6. In an internal combustion engine, a water cooling system including a radiator, a water jacket, connections arranged to give 100 thermosiphonic circulation, a circulating device consisting of a nozzle in the circulating system turned in the direction of circulation, means connecting the nozzle to the exhaust, means for regulating the exhaust 105 pressure in the form of a valve in the exhaust pipe beyond the pipe leading to the nozzle, and means tending to close the valve against slight exhaust pressures permitting the valve to open freely in response to excessive exhaust pressure.

Signed by me at Baltimore, Maryland, this 24th day of September 1915.

NORBERT M. LA PORTE.
